No. 897,739.

PATENTED SEPT. 1, 1908.

F. GROTE.
AUTOMATIC STEAM HEATING SYSTEM.
APPLICATION FILED DEC. 2, 1907.

UNITED STATES PATENT OFFICE.

FERDINAND GROTE, OF EVANSVILLE, INDIANA.

AUTOMATIC STEAM-HEATING SYSTEM.

No. 897,739.

Specification of Letters Patent.

Patented Sept. 1, 1908.

Application filed December 2, 1907. Serial No. 404,651.

To all whom it may concern:

Be it known that I, FERDINAND GROTE, a citizen of the United States, residing at Evansville, in the county of Vanderburg and 5 State of Indiana, have invented certain new and useful Improvements in Automatic Steam-Heating Systems, of which the following is a specification:

My invention relates to an automatic steam 10 heating system, and consists in the construction and arrangement of the several parts, which will be hereinafter fully described, illustrated in the drawings, and particularly pointed out in the claims.

15 The object of my invention is to provide a steam heating system for houses and buildings, which will be automatic in action, and simpler and cheaper to construct and operate than any system heretofore invented and used, and hence more durable and reliable than other heating systems.

20 My invention is illustrated in the accompanying diagrammatic drawing, forming a part of my application.

25 On this drawing, A represents the steam generator, and B, the steam pipe leading from said generator to each of the radiators in the system by branch pipes B', but returning to said generator below the water 30 line.

C represents the main air pipe, leading from radiators D and connected by branch pipes C' from the radiators to the main air pipe C.

35 Each of the branch pipes B' is provided with valves to regulate the flow of steam to the radiators D. The branch pipes C' are without valves, for reasons which will be hereinafter explained.

40 E is a steam trap.

The pipes F, F¹, F², F³ are pipes which conduct the water condensed in the pipes B and B' and the radiators D, which flows back in the pipe B to the generator A below the water line.

45 The operation of my heating system is as follows:—The steam produced in generator A, flows up and out through pipe B, and branch pipes B', to and into radiators D, forcing the air out of said radiators, in turn,

and driving said air through the branch pipes C' into air pipe C.

The air, on its return through pipe C, enters radiator D', the last of the series of radiators, through jet pump G, and is driven 55 through said radiator by the steam from the pipe B. The effect of this pressure of the returning steam on the air in radiator D' is to drive all of the air out of said radiator through pipe a, which leaves the radiator 60 from a more elevated point than the other branch pipe to the steam trap E, which trap when it becomes heated by the steam, closes and thereby prevents the further ingress of air to the system. The effect of this action 65 causes the steam to flow uninterruptedly through the pipes and makes the system automatic. It is due to the fact that the steam and air are hot or in other words so warm as to expand the parts of the thermostatic trap E, 70 that said trap closes, and so long as it is closed, that no air can enter the heating system, and the jet pump will remain open. When once started the system will produce hot steam sufficient to keep the thermostatic 75 trap closed, and in this case, therefore, the operation of the system is automatic, because said trap is closed.

Having thus described my invention and its mode of operation, what I claim and desire to secure by Letters Patent is:

1. In an automatic steam heating system comprising a series of radiators and in combination therewith, a thermostatic trap and a jet pump in connection with the last radiator of the series for receiving and expelling the returning air therefrom through said thermostatic trap, substantially as described.

2. In an automatic steam heating system, the combination with a steam generator and a plurality of radiators, a steam supply pipe leading from the upper portion of the generator and returning to the generator near the base thereof, a main air pipe, valveless branch air pipes leading from the several radiators to a common or main air pipe, a thermostatic steam trap a jet pump in the steam supply connection with the last radiator in the system, said pump having its suction opening connected with the main air 100

pipe, and an air pipe leading from the last radiator to said steam trap, substantially as described.

3. In an automatic steam heating system, the combination with a heat distributing circuit including a series of radiators, an air exhaust pipe, a jet pump, in communication with said air exhaust pipe and the last radiator of the series, of a thermostatic trap to

receive the fluids after they have passed the jet pump, and be closed thereby, substantially as described.

In testimony whereof I affix my signature, in presence of two witnesses.

FERDINAND GROTE.

Witnesses:

ERNST H. RAHM,
WM. HARTMAN.
